UNITED STATES PATENT OFFICE.

WILLIAM McCALLUM, OF YONKERS, NEW YORK, ASSIGNOR TO THE BIGELOW CARPET COMPANY, OF CLINTON, MASSACHUSETTS.

DESIGN FOR A CARPET.

SPECIFICATION forming part of Design No. 12,440, dated August 30, 1881.

Application filed July 29, 1881. Term of patent 34 years.

To all whom it may concern:

Be it known that I, WILLIAM McCALLUM, of Yonkers, county of Westchester, and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The carpet is divided into two prominent portions, A and B, longitudinally. The portion A, which is the main part, has at its edge a longitudinal border, *a*, of ornamental outline, from which project representations *b* of leaves bearing projecting lilies *f* and long slender leaves *e*. In the portion A are also representations *j* of tree-like plants bearing grape-like fruits *k*, and having at their lower parts blossoms *g* and *h*. From the border *a* projects also a bouquet, *c*, having a spray, *d*. The edge of the field A which is nearest to the field B is ornamented with a stripe, *i*, of peculiar design, it being composed of double T-like figures that are set in reverse order in alternate pairs, as shown, and some of them set at right angles to the direction of the stripe.

The portion B of the carpet is composed of three stripes, *n*, *m*, and *o*. The stripe *n* is next

to the stripe *i*, and is an ornamental line. The stripe *m* carries geometrical figures *l*, that are partly overgrown, apparently, by representations of shrubbery. The stripe *o* is divided into narrow sections of ornamental outline, as shown.

I claim—

1. The design for carpets, consisting of the field B, which is composed of the stripes *m*, *n*, and *o*, substantially as shown.

2. The design for carpets, consisting of the stripe *i*, substantially as shown.

3. The design for carpets, composed of the field A, containing the figures *b*, *e*, and *f*, substantially as shown.

4. The design for carpets, consisting of the field A, containing figures *b*, *e*, *f*, *c*, *d*, *g*, *h*, *j*, and *k*, substantially as shown.

5. The design for carpets, consisting of the field A, ornamented with the figures *b*, *e*, *f*, *c*, *d*, *g*, *h*, *j*, *k*, and of the stripes *a* and *i*, substantially as shown.

6. The design for carpets, consisting of the part A, having stripes *a* and *i* and figures *b*, *e*, *f*, *c*, *d*, *g*, *h*, *j*, *k*, and of the part B, having stripes *n*, *m*, and *o* and ornamentation *l*, substantially as shown.

WILLIAM McCALLUM.
